US00D471274S

(12) **United States Design Patent** (10) Patent No.: **US D471,274 S**
(45) Date of Patent: ** Mar. 4, 2003

(54) **MEDICATION DELIVERY PUMP**

DESCRIPTION

(75) Inventors: **Luis A. Diaz**, Yabucoa, PR (US); **David Hershberger**, Kalamazoo, MI (US); **Kris D. Eager**, Richland, MI (US)

FIG. 1 is a top perspective view of a medication delivery pump showing our design;

(73) Assignee: **Stryker Instruments**, Kalamazoo, MI (US)

FIG. 2 is a right side elevational view of the medication delivery pump of FIG. 1;

(**) Term: **14 Years**

FIG. 3 is a top plan view of the medication delivery pump of FIG. 1;

(21) Appl. No.: **29/156,281**

FIG. 4 is a bottom plan view of the medication delivery pump of FIG. 1;

(22) Filed: **Feb. 23, 2002**

FIG. 5 is a left side elevational view of the medication delivery pump of FIG. 1;

(51) LOC (7) Cl. **24-02**

FIG. 6 is a rear elevational view of the medication delivery pump of FIG. 1;

(52) U.S. Cl. **D24/111**

FIG. 7 is a front elevational view of the medication delivery pump of FIG. 1;

(58) Field of Search D24/111, 108;

FIG. 8 is a top perspective view of a second embodiment of a medication delivery pump showing our design;

D15/8; 604/132, 131, 246, 890.1, 66, 65,

67; 417/478; 128/DIG. 12

FIG. 9 is a right side elevational view of the medication delivery pump of FIG. 9;

(56) **References Cited**

FIG. 10 is a top plan view of the medication delivery pump of FIG. 9;

U.S. PATENT DOCUMENTS

FIG. 11 is a bottom plan view of the medication delivery pump of FIG. 9;
